“Women’s Renew Ride Running Shoe”; Famous Footwear; retrieved Jun. 5, 2020; disclosure date unknown but prior to the filing date of the present application; URL: <https://www.famousfootwear.com/en-US/Product/98543-1048348/Nike/White_Pink/Womens+Renew+Ride+Running+Shoe.aspx>.

Primary Examiner — T Chase Nelson(74) Attorney, Agent, or Firm — Banner & Witcoff, Ltd.(57) CLAIM

The ornamental design for a shoe, as shown and described.

DESCRIPTION

FIG. 1 is a front perspective view of a shoe showing my new design;
 FIG. 2 is a side view thereof;

FIG. 3 is a rear perspective view thereof;

FIG. 4 is a cross-section taken through line 4-4 in FIG. 2; and,

FIG. 5 is a cross-section taken through line 5-5 in FIG. 2. The broken lines immediately adjacent to the shaded area define the bounds of the claimed design and form no part thereof. The broken lines depicting the remainder of the shoe form no part of the claimed design.
